UNITED STATES PATENT OFFICE.

ADOLFO DE CLAIRMONT, OF TOPEKA, KANSAS, ASSIGNOR OF ONE-FOURTH
TO T. D. HUMPHREYS, OF TOPEKA, KANSAS.

REFRIGERATOR.

SPECIFICATION forming part of Letters Patent No. 698,453, dated April 29, 1902.

Application filed August 30, 1901. Serial No. 73,811. (No model.)

To all whom it may concern:

Be it known that I, ADOLFO DE CLAIRMONT, a citizen of the United States, residing at Topeka, in the county of Shawnee and State of 5 Kansas, have invented certain new and useful Improvements in Refrigerators; and I do hereby declare the following to be a full, clear, and exact description of the invention, such as will enable others skilled in the art to which 10 it appertains to make and use the same.

The primal object of this invention is a rarefied-air space in double-walled structures to greatly retard the passage of heat and cold. In refrigerator construction a saving of about 15 fifty per cent. of ice results, which is of material advantage. In house and like construction fuel is saved in cold weather for heating, and in warm weather the house or building is rendered cooler than would be 20 possible if no obstacle were interposed to the penetration of heat-rays. Refrigerator-cars and like cold-storage carriers are enabled to have the storage capacity for provisions increased compared with similar transporting 25 structures of like size as generally provided. Less ice being required, the weight of the refrigerators is diminished. Hence a saving of energy and propulsive power results. The space between the walls must be hermetically 30 sealed, and the air is exhausted therefrom to a practicable degree by means of a pump or other contrivance.

While the vital feature of a rarefied atmosphere in the space of hollow walls is para- 35 mount, yet the invention contemplates the novel structural features which hereinafter will be more fully described and claimed and which are illustrated in the annexed drawings, in which—

40 Figure 1 is a perspective view of a refrigerator embodying the invention, a portion of one of the sides being broken away. Fig. 2 is a plan section. Fig. 3 is a detail view showing more clearly the hinge connection 45 between a door and a side of the refrigerator, whereby communication is established between these parts. Fig. 4 is a section about on the line X X of Fig. 3. Fig. 5 is a detail view showing the valve-controlled port be- 50 tween the spaces of adjacent walls. Fig. 6 is a view of the parts shown in Fig. 4 with

the door thrown open, so as to bring the passages of the hinge members into register. Fig. 7 is a perspective view of a hollow glass panel or light. Fig. 8 is a section of the said 55 panel.

Corresponding and like parts are referred to in the following description and indicated in all the views of the drawings by the same reference characters.

While the invention is illustrated in connection with a refrigerator, it is to be understood that it is designed for general use in connection with structures of any kind having 60 hollow or double walls.

The refrigerator shown is of the type commonly employed for domestic purposes, its top, front, back, bottom, and sides being hollow and access being had thereto by means of the door 1, leading to the provision-chamber, and the door 2, opening into the ice-compartment. These doors are likewise hollow. The space inclosed between the several walls of the sides and doors of the refrigerator is hermetically sealed, and the air is exhausted 70 therefrom by means of a valved nipple or pipe, such as commonly employed in pneumatic devices, the valve opening outward instead of inward. For convenience in exhausting the air from the several parts of the refrigerator or structure a single nipple or pipe 75 3 is provided and conveniently located, being applied to the back of the refrigerator in the present instance. The top, bottom, and sides have communication with the back, and the 80 front may be in communication with any one of the sides. Valves 4, of any design or make, are employed for controlling communication between the several air-spaces of the structure, so that after the air has been exhausted 85 90 the several walls may be isolated, thereby preventing the admission of air into the spaces of all the walls should a defect or leak exist in any one of the walls. The hollow spaces of the doors 1 and 2 are in communication 95 with the hollow spaces of the walls to which they are attached through the hinges, which are formed with passages. Obviously within the purview of the invention any means may be provided which will establish communication 100 between the doors and the parts to which they are hinged. The hinges are preferred,

since they obviate the necessity of providing independent means for establishing communication between the doors and part to which they are attached. The hinge member 5 is provided with the pintle 6, and a passage 7 is formed therein. The hinge member 8 is formed with the sleeve 9, which fits over the pintle 6 and has a passage 10, which is in communication with the air-space of the part to which the member 8 is attached. When the hinge members are extended, as shown in Figs. 3 and 4, the passages 7 and 10 are out of register and communication between the space of the door and the space of the part to which the door is hinged is interrupted. When the door is thrown open to the limit of its movement, as indicated in Fig. 6, the passages 7 and 10 are brought in register and communication between the door and the part to which the door is hinged is established. It seldom happens in ordinary usage that the door is thrown back against the part to which it is hinged. Hence normally communication between the door and part to which the door is hinged is cut off. When it is required to exhaust the air from the walls of the refrigerator, the valves 4 are opened and the doors are thrown back to the limit of their movement, thereby admitting of exhaustion of the air from all parts of the refrigerator at one and the same time. After the air has been exhausted the several spaces of the walls and doors are isolated by closing the valves 4 and by closing or partly closing the doors. The ends of the passages 7 and 10 bordering upon the hinge-joint are extremely narrow. Hence a slight movement of the door suffices to throw the passages 7 and 10 out of register. The pintle 6 being tapering and the sleeve 9 of a corresponding taper and the parts fitted by a ground joint, leakage at the joint between the hinge members is obviated.

The door 1, leading into the provision-chamber, is provided with a glass panel or light 11, which is hollow, the air being exhausted from the space. This panel or light may be applied to any side of the refrigerator or may be used in structures generally and is admirably adapted for passenger-cars and buildings.

50 By having the air exhausted from the space

between the walls of the panel or light the glass is not dimmed by moisture condensing thereon, which is the chief source of annoyance in using double panes of glass in dwellings, passenger-cars, and other places. In 55 order to prevent collapsing of the walls of the light or panel, a brace 12, of glass, is located in the space formed between said walls and is secured thereto by transparent cement. Hence the vision is not obstructed and the presence 60 of the brace is not perceptible.

Having thus described the invention, what is claimed as new is—

1. In a structure having hollow walls from which the air is adapted to be exhausted, a 65 valve-controlled communication between said walls for isolating the same after the vacuum has been created, substantially as and for the purpose set forth.

2. A refrigerator or like structure having 70 hollow walls from which air is adapted to be exhausted by application of a pump to a side or wall of the structure, and valve-controlled communications between the spaces of the several walls to admit of each being isolated 75 after exhaustion of the air, substantially as set forth.

3. In a structure having a hollow wall and a hollow door, a hinge connection between the door and wall, and hinge members having 80 passages in communication with, respectively, the wall and the door, said passages being normally out of register to interrupt communication between the hollow spaces of the wall and door and adapted to be brought into co- 85 incident relation by throwing the door open to the limit of its movement, substantially as set forth.

4. A hollow glass panel or window-light having the air exhausted therefrom and having a transparent brace attached at its ends to opposite walls of said hollow glass panel, substantially as set forth.

In testimony whereof I affix my signature in presence of two witnesses.

ADOLFO DE CLAIRMONT.
